DEVICE FOR SKETCHING AND CUTTING
OUT SEGMENTS OF METAL

Filed Oct. 17, 1963, Ser. No. 316,982
3 Claims. (Cl. 33—21)

Spherical containers used for storing gas under pressure, or as reservoir for water or the like, are usually 10 constructed of steel plate segments. To date, these segments have been cut out, for the particular case and requirements by a trial and error method, of even plates with a size corresponding to rim allowance. After flanging of the plates to the prearranged radius, there occurs 15 the finishing cutting of the segments by hand or according to pattern. Despite this there are still considerable inaccuracies so that in most cases a further cutting during construction is unavoidable.

It is an object of the present invention to produce a device in which, from flanged plates at a required spherical radius, spherical segment plates can be sketched or cut out correctly as to rim and angle sketched.

This problem is solved by having a collar positioned about a turnable or rotatable Cardanic ring system concentric to a supported pivoted operating arm which is supported over a raw partial ball which is to be formed into the finished segment.

The device consists essentially of a Cardanic ring system, containing three or four rings, which is supported by a collar situated on supports, wherein the inner ring of the Cardanic ring system has a swivel arm arranged concentrically stationary and perpendicularly on a turnable shaft so that it pivots about the shaft axis. This swivel arm, the lower point of which serves for sketching, can also be replaced by a correspondingly arranged metal cutting burner. According to a flanging of the plates to be undertaken before the sketching and cutting, it is possible with the help of this device to sketch and cut segments with an unexpectedly high theoretical precision.

Other objects and advantages of the invention will become apparent from a study of the following description and drawing wherein:

FIGURE 1 is a perspective of the apparatus according to the invention;

FIGURE 2 is a top view of the apparatus of FIGURE 1; and

FIGURE 3 is a section taken along lines 3—3 of FIGURE 2.

As seen in FIGURES 1-3 of the drawing, four leg supports A which are resistant to bending are flexibly secured at their upper ends at an upper collar B and at their lower ends to a base plate G. The length of the supports A can be varied since the legs are of the telescopic type. These legs support collar B which in turn supports a Cardanic ring system C. This ring system consists of rings D₁, D₂, D₃ and D₄ (FIGURE 2), which in the known Cardanic fashion are supported in a swiveling manner by pins in order always to be staggered at 90° from each other and within each other. As shown in the drawings, pin locking means are provided in the system such as illustrated for shaft E on ring D₁ and on the pin between rings D₁ and D₂. The outer ring D₄ rests turnably in collar B. The innermost ring D₁ displays a turnable shaft E to which a telescopically extendable swivel arm F is arranged concentrically, perpendicularly and stationary toward the bottom portion of the apparatus. The legs A rest on base plate G at which a three-point support H is provided as the support for the segment plates which support is changeable for fitting to the actual radius. It should be pointed out that

2

the supporting legs A are exchangeable or changeable in their length.

From most of the skin sections of the sphere, it can be seen that for the format and arrangement of the segment plates the spheric biangular systems are the basis from which are obtained the number of segments. Complete spherical biangles, for example, extending from pole to pole, are undesirable, because of the difficulties arising from soldering. Therefore, spherical biangular formats are preferred where the long pointed end pieces have been omitted. Hence, the necessity arises to provide more than one segment format, and it has also been possible to develop divisions which in such cases come out with two or three segment sizes. However, from the number of the spheric biangles constituting the basis of the division, corresponding spheric center angles can constantly be achieved which are necessary for the introduction of the individual rings of the Cardanic ring system of the device according to the invention. With the arrangement of the rings to these angles, which arrangement is effected by the deviation from the horizontal position, the arrangement of the swivel arm is necessarily also connected. By the fixed motion of the swivel arm, the cutting and sketching head indicates the cutting line by swinging on the underlying metal. It is in accordance with the invention to bring a "raw" segment metal corresponding in form and size as concentrically as possible under the Cardanic ring system. The pivotable rings are then manipulated so that arm F is inclined to move about the axis of shaft E in such a manner as to contact the "raw" segment along a predetermined line defining the boundary of the finished segment. Accordingly, by proper angular arrangement of the rings, a side of the segment is formed. As a result, with this proper positioning of the rings with respect to each other and by rotation of the entire system in collar B, it is possible to form a spherical segment without the necessity of disturbing the mounting of the device or of the workpiece.

The Cardanic ring system represented with four rings in the process example of the present device can naturally also exist with three rings. In the arrangement of three rings (D₁, D₂, D₃), the outer ring (D₃) together with the collar B takes over the function of the outer ring existing with four rings. The arrangement of four rings, however, simplifies the dislocation (turning 90°) of the total ring system.

Obviously many modifications and variations of the present invention are possible in the light of the above teachings. It is, therefore, to be understood that within the scope of the appended claims the invention may be practiced otherwise than as specifically described.

Thus the Cardanic ring system, instead of being supported by legs, can be mounted, for instance, hanging down without vibration from the ceiling of a factory hall. In order to make possible a remote control in case of large distances between metal and Cardanic ring system mechanical or electric preselecting and control devices can be provided for adjusting the ring system.

What is claimed is:

1. A device for forming spherical segments comprising a collar, a Cardanic ring system including an inner ring, an outer ring and at least one intermediate ring, said outer ring being rotatably mounted in said collar, pivot means securing each of said rings to its adjacent rings, the pivot means between each pair of said rings being 90° apart from the pivot means of the adjacent pair of rings, a shaft extending diametrically across said inner ring, an operating arm rotatably mounted on said shaft with said shaft constituting the axis of rotation of said

arm, locking means in said inner for fixing said shaft relative to the inner ring and locking means on said intermediate ring for fixing the inner ring relative to the intermediate ring, a cutting instrument disposed at the end of said operating arm, a base plate, a three-pointed support on said base plate for a concentric seating of a work piece under the center of said Cardanic ring system with said cutting instrument disposed slightly above said support whereby said cutting instrument may contact the workpiece to form a spherical segment out of said workpiece, and support means for mounting said collar above said base plate.

2. A device as set forth in claim 1 wherein said support means for mounting said collar above said base plate comprises a plurality of telescopic legs connected at one end to said base plate and at the other end to said collar.

3. The device according to claim 1 wherein said Cardanic ring system includes four individual rings.
